[57] CLAIM

The ornamental design for a rotary spreader, substantially as shown and described.

DESCRIPTION

FIG. 1 is a perspective view of a spreader showing my new design;

FIG. 2 is a side elevational view thereof;

FIG. 3 is a front elevational view thereof;

FIG. 4 is a top plan view thereof; and

FIG. 5 is a rear elevational view thereof.

The handle in FIGS. 3-5 is shown broken away for ease of illustration.

FIG. 1

FIG. 2

FIG. 3

FIG. 4

FIG. 5
